UNITED STATES PATENT OFFICE.

BAXTER P. HAMILTON, OF BROOKLYN, NEW YORK, ASSIGNOR TO AMERICAN TELEPHONE AND TELEGRAPH COMPANY, A CORPORATION OF NEW YORK.

CARRIER TELEGRAPH CIRCUITS.

Application filed October 21, 1920. Serial No. 418,484.

To all whom it may concern:

Be it known that I, BAXTER P. HAMILTON, residing at Brooklyn, in the county of Kings and State of New York, have invented certain Improvements in Carrier Telegraph Circuits, of which the following is a specification.

This invention relates to signaling systems and, more particularly, to signaling systems in which telegraph signals may be transmitted by means of carrier currents.

One of the objects of the invention is to provide an arrangement whereby an ordinary subscriber's circuit or loop of a telegraph system may be associated with the channels of a multiplex system. A further object of the invention is to provide arrangements in a system of the character just described, whereby, in two-way transmission of telegraph signals, the received signals will not react upon the transmitting apparatus so as to be transmitted back in the direction from which they originated.

Other and further objects of the invention will be clear from the following description, when read in connection with the accompanying drawing, Figure 1 of which is a circuit diagram of one form of the invention and Fig. 2 of which is a circuit diagram of a modified form of the invention.

Referring to Fig. 1, ML designates a main transmission line over which two-way transmission may take place by means of carrier currents. Outgoing transmission may be impressed upon the line LM by means of a carrier transmitting circuit TL, while received transmission may be taken from the line ML through carrier receiving circuit RL. In order to render the circuits RL and TL substantially conjugate, the circuit RL is associated with the main line ML through a well-known form of balanced transformer 10, and an artificial line or network MN is provided for balancing the main line ML.

As many carrier channels as desired may be associated with the circuits TL and RL through tuned circuits, in a well-known manner. For purposes of illustration, but one channel is shown associated with each circuit, it being understood, however, that in practice additional channels may be provided. The transmitting channel illustrated is associated with the common trans-

mitting circuit TL through a tuned circuit arrangement TF and comprises a vacuum tube amplifier TA and a vacuum tube generator G. The receiving channel is associated with the common receiving circuit RL through a similar tuned circuit arrangement RF and includes a vacuum tube detector D and a receiving relay R. A subscriber's loop L, including a key K and sounder S, is provided, and the circuit of the subscriber's loop is controlled by means of a repeating relay 11, controlled by the receiving relay R, so that received signals may be repeated from the receiving carrier channel of the subscriber's loop. A central office sounder S' is also controlled by the repeating relay 11. A transmitting relay T is included in the subscriber's loop, said transmitting relay being in series with the relay 11, which controls a monitoring sounder S'' at the central office, so that telegraph signals originating in the loop will be indicated by said sounder. A transmitting key K' may be also provided in the transmitting portion of the loop at the central office. The contacts of the sounder S'' are arranged to short-circuit the contacts to the receiving relay R when signals are being transmitted, in order that if the receiving operator desires to "break in," the received signals cannot be repeated to the loop while the break signal is being transmitted. A condenser C is associated with the transmitting relay T and is controlled by contacts of the repeating relay 11, for the purpose of momentarily holding the transmitting relay energized while the armature of the repeating relay 11 is operating in response to received signals, thus preventing the received signals from being repeated back to the carrier circuit by the transmitting relay T. The transmitting relay T controls a circuit 13 for short-circuiting the input circuit of the amplifier TA, thereby preventing the transmission of oscillations from the generator G.

The operation is as follows: Normally, when signals are not being transmitted, the carrier frequency of the channel is sent out with uniform amplitude. Consequently the frequency assigned to the receiving channel will be received from the main line in the circuit RL and selected by the tuned circuit arrangement RF to be impressed upon the detector D, thereby causing a steady direct

current to flow through the receiving relay R. It will be understood that the grid circuit of the detector D has such a potential impressed upon it by means of the grid battery, that when the carrier frequency is not being received, no current flows in the output circuit. The steady current flowing through the relay R maintains the repeating relay 11 energized over a circuit from 5 battery over the front contact of the relay R through the winding of the relay 11. Relay 11 holds the circuit of the subscriber's loop 11 normally closed over a circuit from positive battery through the sounder S over 10 a key K, front contact of relay 11, through the winding of relay 12, over key K' and through the winding of transmitting relay T to negative battery. The sounder S, relay 12, and transmitting relay T, are, therefore, energized. 15

With the circuit in the condition just described, the operator of the loop circuit may transmit signals by opening the key K or the operator at the central office may transmit by opening the key K'. In either case, the sounder S, relay 12, in transmitting relay T, will be de-energized. The relay T, which normally holds open the controlling circuit 13, upon being energized, closes said 20 circuit to short-circuit the input circuit of the amplifier TA. With the circuit 13 open, the generator G generates oscillations which are impressed upon the input circuit of the amplifier TA and after being amplified, are 25 transmitted through the tuned circuit TF and over the circuit TL to the main line ML. Upon closing the circuit 13, however, a path for the high frequency generated by the generator G is provided through the 30 condenser 14 to ground, so that substantially no carrier currents are transmitted through the amplifier TA. The interruptions of the transmission of the carrier frequency operate the receiving apparatus at 35 the distant end of the line ML. The de-energization of relay 12, in the meantime, opens the circuit of the central office sounder S' which, in turn, over its back contact, short-circuits the contacts of the receiving 40 relay R.

Should an operator at the distant end of the main line interrupt the carrier frequency transmitted to the receiving channel, the direct current from the relay R will 45 be interrupted and the relay de-energized, thereby opening the circuit of the repeating relay 11. The de-energization of the repeating relay opens the circuit of the sounder S' and also opens the circuit of the 50 loop L through the sounder S, relay 12, and transmitting relay T. The sounder S consequently registers the signal at the loop operator's station. In the normal closed condition of the loop, the condenser C acquires 55 a charge. When, however, the loop is

opened by the de-energization of the repeating relay 11, the condenser C discharges through the windings of the relay 12 and the transmitting relay T, during the moment that the armature of the relay 11 is 60 shifting from its front to its back contact. This discharge holds the relay 12 and the transmitting relay T energized until the armature of the relay 11 rests upon its back contact, when the holding circuit for said 65 relays is provided from ground over the back contact of the relay 11, through the winding of the relay 12 over key K' and through the winding of the relay 12 over key K' and through the winding of relay T to 70 negative battery. The relay 12 and the transmitting relay T do not, therefore, respond to the opening of the loop circuit at the repeating relay 11, and the received signal is not transmitted back over the transmitting carrier channel to the line ML. At 75 the end of the interruption of the received frequency just described, current again flows through the receiving relay R, closing the circuit of the repeating relay 11, which 80 again closes the loop. The condenser C, which has again acquired a charge, discharges through the winding of the relay 12 and the transmitting relay T, to hold said 85 relays energized, while the armature of the 90 repeating relay moves from its back to its front contact.

If, while signals are being received, it should be desired to interrupt the sending operator, in order to transmit in the opposite direction, a break signal may be transmitted by holding open the key K or the key K'. This results in the de-energization 95 of the relay 12 and the transmitting relay T. The transmitting relay T, by closing the circuit 13, interrupts the transmission of the carrier frequency to the distant station, while the relay 12 opens the circuit of sounder S' which, in turn, at its back contact, short-circuits the contacts of the receiving relay R, so that the repeating relay 100 105 110 115 120 125 130 135 140 145 150 155 160 165 170 175 180 185 190 195 200 205 210 215 220 11 is again energized and the sounder S'' opens the short circuit about the contacts of the receiving relay R. The relay 11 is at once deenergized and opens the loop circuit 5 in the manner already described, at the same time locking up the relay 12 and the transmitting relay T, over the back contact of relay 11. The sounder S'' is, therefore, held energized to maintain the shunt circuit about the receiving contacts of the relay R open.

The conditions just described obtain as long as the break signal is being transmitted. The operator who is transmitting by means 15 of the key K, will at once recognize that a break signal is being received, by reason of the fact that the sounder S no longer responds to the actuation of the key K, since the loop circuit is held open. The operator 20 will, therefore, close the key K and the operator who is "breaking in" will, after transmitting the break signal a short interval, begin to send in the regular manner, whereupon the circuit illustrated functions 25 to receive in the manner already described.

A somewhat similar arrangement is illustrated in Fig. 2, differing from that of Fig. 1 however, in that, instead of the condenser discharge arrangement for holding the relay 12 and the transmitting relay T, a magnetic locking feature is provided. For this purpose, the relay 12, instead of being provided with a single coil, as in Fig. 1, is provided with a main coil 12', which is included in the loop circuit, and an auxiliary coil 12'', which is controlled by the repeating relay 11, the coil 12'' acting as a holding coil. The circuit of the loop does not, in this instance, include the transmitting 40 relay T, but passes only through the coil 12' of the relay 12 and the key K'. The transmitting relay T is arranged in a local circuit controlled by the relay 12. The receiving sounder S' is also arranged in a slightly different manner, being connected 45 in series with the relay 11, instead of being in a local circuit controlled by said relay.

The operation is as follows: Repeater relay 11 and sounder S' are normally energized as before. The relay 11 at one of its front contacts, short-circuits the coil 12'' of the relay 12, so that said coil is de-energized. The relay 11 holds the loop circuit L closed over the circuit as follows: from battery 55 to the sounder S, key K, front contact of relay 11 and the coil 12' of the relay 12. The coil 12' of the relay 12 holds the armature of said relay attracted so that the circuits of the transmitting relay T and of the 60 transmitting sounder S'' are closed. Upon opening the loop circuit by means of the key K or the key K', the coil 12' is deenergized and the armature of the relay 12 falls off, so that the transmitting relay T is de-energized to interrupt the transmission of

the carrier frequency to the distant station. The sounder S'' is, at the same time, de-energized and short-circuits the contacts of the receiving relay R. Upon again closing the transmitting key, the circuit will be restored to its original condition and the carrier frequency again transmitted.

Interruptions of the received carrier frequency cause the de-energization of the receiving relay R. The circuit of the repeating relay 11 and the sounder S' are opened and the relay 11 opens the circuit of the loop, including the circuit of the coil 12' of the relay 12. The short-circuit about coil 12'' is removed, at the same time, however, so that the relay 12 is maintained energized during the interruptions of the loop circuit and the received signals cannot be transmitted back to the main line ML by the operation of the transmitting relay T.

If, while signals are being received, the operator at the loop position desires to interrupt or "break in," the key K may be opened. This is without effect if the receiving relay is de-energized at that moment, but as soon as the receiving relay is again energized to short-circuit the coil 12'', the armature of the relay 12 will fall off, since both coils 12' and 12'' are de-energized. The transmitting relay T and the sounder S'' are de-energized, the transmitter functioning to interrupt the transmitting frequency while the sounder S'' short-circuits the contacts of the receiving relay R and holds the sounder S' and the repeating relay 11 energized as long as the break signal continues. The received signals, therefore, are not repeated to the loop during the continuance of the break.

The effect of a break signal received from the distant station is to cause the de-energization of the receiving relay R during the continuance of the break. If, at this moment, the loop L is opened for the transmission of a space signal, the sounder S'' will be de-energized and the de-energization of the relay R will be without effect. As soon, however, as the key in the loop is again closed to transmit a dot or a dash, the coil 12' is energized to close the circuits of the transmitting relay T and sounder S'', consequently, the sounder S'' removes the short circuit from about the contacts of the relay R and the repeating relay 11 is at once de-energized to open the loop circuit. The de-energization of the relay 11, by removing the short-circuit from the coil 12'' causes the energization of said coil and further interruption of the loop by means of the key K or the key K' is without effect, since the relay 12 remains energized to hold the sounder S'' energized, thereby preventing any possibility of short-circuiting the contacts of the relay R, and the opening of the loop by means of the relay 11, prevents the

sounder S from responding to the transmitted signals. The operator at the loop, by observing that the sounder no longer follows the transmitting key, knows at once 5 that a break signal is being transmitted.

It will be obvious that the general principles herein disclosed may be embodied in many other organizations widely different from those illustrated, without departing 10 from the spirit of the invention, as defined in the following claims.

What is claimed is:

1. In a signaling system, a carrier line, a carrier transmitting channel to transmit 15 over said line, a carrier receiving channel to receive from said line, means to render said transmitting and receiving channels substantially conjugate with respect to each other, a low frequency direct current tele- 20 graph circuit, a transmitting relay associated with said circuit and arranged to control said carrier transmitting channel, a receiving relay associated with said carrier receiving channel and arranged to control 25 said telegraph circuit, and means to prevent said transmitting relay from responding to signals received by said receiving relay.

2. In a signaling system, a carrier line, a carrier transmitting channel to transmit 30 over said line, a carrier receiving channel to receive from said line, means to render said transmitting and receiving channels substantially conjugate with respect to each other, a direct current telegraph circuit, a transmitting relay associated with said tele- 35 graph circuit and responding to changes in the condition of said circuit to control said transmitting channel, a receiving relay as- 40 sociated with said receiving channel and re- 45 sponding to signals received by said channel to produce changes in said telegraph circuit similar to those actuating the transmitting relay, and means for preventing said trans- 50 mitting relay from being actuated by said receiving relay.

3. In a signaling system, a carrier line, a carrier transmitting channel to transmit over 55 said line, a carrier receiving channel to re- 60 ceive from said line, means to render said transmitting and receiving channels substan- 65 tially conjugate with respect to each other, a direct current telegraph circuit, a trans- 70 mitting relay associated with said telegraph circuit and operating in response to changes 75 from current to no current condition in said circuit, and vice versa, to control said trans- 80 mitting channel, and a receiving relay as- 85 sociated with said receiving channel and 90 operating in response to signals received in 95 said channel to produce in said telegraph circuit changes from current to no current condition and vice versa, and means to prevent 100 said transmitting relay from being actuated by said receiving relay.

4. In a signaling system, a carrier line, a carrier transmitting channel to transmit over said line, a carrier receiving channel to receive from said line, means to render said transmitting and receiving channels sub- 10 substantially conjugate with respect to each other, a direct current telegraph circuit, a transmitting relay associated with said tele- 15 graph circuit and operating in response to makes and breaks of said circuit to control 20 said transmitting channel, a receiving relay associated with said receiving channel and operating in response to signals received in 25 said channels to produce makes and breaks in said telegraph circuit, and means for pre- 30 venting said transmitting relay from re- 35 sponding to the action of said receiving relay.

5. In a signaling system, a carrier line, a carrier transmitting channel to transmit 35 over said line, a carrier receiving channel to receive from said line, means to render said transmitting and receiving channels sub- 40 stantially conjugate with respect to each other, a direct current transmitting relay as- 45 sociated with a telegraph circuit and re- 50 sponsive to current changes in said tele- 55 graph circuit to control said transmitting channel, a receiving relay associated with 60 said receiving channel and responsive to sig- 65 nals received in said channel to produce cur- 70 rent changes in a telegraph circuit similar 75 to those actuating said transmitting relay.

6. In a signaling system, a carrier line, a carrier transmitting channel to transmit 80 over said line, a carrier receiving channel to receive from said line, means to render said transmitting and receiving channels sub- 85 stantially conjugate with respect to each other, a transmitting relay associated with a telegraph circuit and responsive to changes 90 from current to no current condition in said circuit and vice versa, to control said trans- 95 mitting circuit, a receiving relay associated 100 with said receiving channel and responsive to signals received in said channel to pro- 105 duce changes from current to no current condition and vice versa, in a telegraph cir- 110 cuit.

7. In a signaling system, a carrier line, a carrier transmitting channel to transmit over said line, a carrier receiving channel to receive from said line, means to render said transmitting and receiving channels sub- 115 stantially conjugate with respect to each other, a transmitting relay associated with a telegraph circuit and responsive to makes 120 and breaks in said circuit for controlling said transmitting channel, a receiving relay associated with said receiving channel and 125 responsive to signals received in said channel for producing makes and breaks in a tele- 130 graph circuit.

8. In a signaling system, a carrier line, a carrier transmitting channel to transmit 130

- over said line, a carrier receiving channel to receive from said line, a direct current telegraph circuit, a transmitting relay associated with said circuit and responsive to signals transmitted over said circuit to control said transmitting channel, a receiving relay associated with said receiving channel and responsive to signals received in said channel to control said telegraph circuit, and means whereby when said transmitting relay is actuated the receiving relay is prevented from controlling said telegraph circuit.
9. In a signaling system, a carrier line, a carrier transmitting channel to transmit over said line, a carrier receiving channel to receive from said line, a direct current telegraph circuit, a transmitting relay associated with said telegraph circuit and responsive to changes from current to no current condition in said circuit and vice versa to control said transmitting channel, a receiving relay associated with said receiving channel and responsive to signals received in said channel to produce changes from current to no current condition and vice versa in said telegraph circuit, and means whereby when said transmitting relay is actuated said receiving relay is prevented from producing changes in said telegraph circuit similar to those actuating the transmitting relay.
10. In a signal system, a carrier line, a carrier transmitting channel to transmit over said line, a carrier receiving channel to receive from said line, a direct current telegraph circuit, a transmitting relay associated with said circuit and responsive to makes and breaks in said circuit to control said transmitting channel, a receiving relay associated with said receiving channel and responsive to signals received in said channel to produce makes and breaks in said telegraph circuit, means to prevent said receiving relay from producing makes and breaks in said telegraph circuit when said transmitting relay is actuated.
11. In a signaling system, a carrier line, a carrier transmitting channel to transmit over said line, a carrier receiving channel to receive from said line, a direct current telegraph circuit, a transmitting relay associated with said telegraph circuit and responsive to signals transmitted over said circuit to control said carrier transmitting channel, a receiving relay associated with said receiving channel and responsive to signals received in said channel to transmit over said telegraph circuit, and means operative when said transmitting relay responds to a signal transmitted over said telegraph circuit to short-circuit the contacts of said receiving relay.
12. In a signaling system, a carrier line, a carrier transmitting channel to transmit over said line, a carrier receiving channel to receive from said line, a direct current telegraph circuit, a transmitting relay associated with said telegraph circuit and responsive to signals transmitted over said circuit to control said transmitting channel, a receiving relay associated with said receiving channel and responsive to signals received in said channel for transmitting signals to said telegraph circuit, and means whereby said transmitting relay is prevented from responding to signals attempted to be transmitted over said telegraph circuit when a continuous break signal is received in said carrier receiving channel.
13. In a signaling system a carrier transmitting channel, means associated with said channel for translating low frequency signals into carrier currents, said means including a vacuum tube oscillator for supplying the carrier frequency and a vacuum tube for controlling the transmission of the carrier frequency from the oscillator to the line, together with means for determining the action of said last mentioned vacuum tube in accordance with telegraph signals, a low frequency telegraph circuit and a mechanical telegraph repeater for repeating telegraph signals from said low frequency telegraph circuit to said carrier transmitting channel to control the operation of said last mentioned vacuum tube.
14. In a signaling system, a carrier line, a carrier transmitting channel to transmit over said line, including means for translating low frequency signals to carrier currents, a carrier receiving channel to receive from said line including means for translating carrier currents into low frequency signals, means to render said transmitting and receiving channels substantially conjugate with respect to each other, a low frequency direct current telegraph circuit and a mechanical two-way telegraph repeater for associating said telegraph circuit with said transmitting and receiving channels, whereby low frequency telegraph signals may be repeated from said telegraph circuit to said transmitting channel and whereby carrier signals received in said receiving channel may be repeated as low frequency signals to said telegraph circuit.

In testimony whereof, I have signed my name to this specification this 18th day of October, 1920.

BAXTER P. HAMILTON.
